UNITED STATES PATENT OFFICE.

JOHN J. SMITH, OF ALLSTON, MASSACHUSETTS.

PELT STRETCHER.

Application filed August 7, 1926. Serial No. 127,938.

The invention relates to hide or pelt stretchers particularly of that type adapted to be used for the purpose of curing furbearing skins and is an improvement on my prior 5 United States Patent No. 1,667,295 granted Apr. 4, 1928. One object of the present invention is to provide an improved stretcher embodying a spring frame which is adjustable to adapt itself to pelts of different sizes 10 wherein the device is provided with improved means for holding the spring frame within the pelt in stretched condition, such means being in the form of an improved spreader bar connecting the spring arms of the frame 15 together and adapted to be readily and easily manipulated.

A further object of the invention is to provide improved means for locking the spreader bar in various adjusted positions to the spring 20 arms of the frame to hold the tail piece of the pelt in stretched condition.

Other objects of the invention will appear in the following description and appended claims reference being had to the accompanying drawings forming a part of this specification wherein like reference characters indicate corresponding parts in the several views, wherein

Fig. 1 is a plan view illustrating a stretching apparatus constructed in accordance with my invention.

Fig. 2 is a similar view illustrating the pelt or fur in position upon the frame, and

Fig. 3 is a sectional view taken substantially on the line 3—3, Fig. 1.

Figs. 4 and 5 are diagrams illustrating the method of locking the spreader bar to the side arms of the frame.

Referring to the drawings wherein I have 40 illustrated a present preferred embodiment of my invention it will be seen that the stretcher comprises a spring frame which is preferably formed from a relatively heavy wire bent intermediate its upper ends at 9 to 45 form a nose and extending downwardly to form spring arms 10 and 11. The spring arm 10 is somewhat longer than the opposite arm 11, and at its lower end is bent substantially at right angles and inwardly to form a 50 connecting arm 12, the free end of which passes through an eye or loop 13 formed at the lower end of the spring arm 11. The transverse connecting arm 12 at the left-hand side as viewed in Figs. 1 and 2, is bent into an 55 upturned portion 14 for interlocking the spring arms together and preventing the por-

tion 12 from becoming disconnected from the eye or loop 13. The wire constituting the spring frame embodying the invention is smooth throughout, having no projections or teeth struck up from the inner edges of the spring arm as in my prior application above referred to.

From the foregoing construction it will be seen that the spring arms 10 and 11 may be contracted and expanded under tension, and in order to connect the arms together in adjusted positions with respect to each other a spreader bar S is provided. This bar may be formed from a flat metal plate 15. (see particularly Fig. 3) which at one end is stamped out or otherwise formed to provide a longitudinal guide slot 16 adapted to slidably receive the spring arm 10. The plate 15 is also stamped or otherwise formed at its opposite end to provide a similar longitudinal guide slot 17. The slot 16 at its upper longitudinal edge as viewed in Fig. 3 is formed with a plurality of spaced projections or teeth 18 forming therebetween recesses or notches 20 of sufficient size to receive the arm 10 therein. In like manner the longitudinal guide slot 17 at its upper edge is provided with a corresponding series of projections or teeth 19 forming therebetween recesses or notches 21 for receiving the spring arm 11. 85

The recesses 20 and 21 are of a width somewhat greater than the thickness of the wire constituting the side arms 10 and 11 as shown in Fig. 4 wherein the spreader bar S is in normal or longitudinal position which it occupies when there is no pelt on the frame. These recesses are defined by substantially parallel faces f formed at the sides of the teeth 18 and 19 and extending from the top surface t to the bottom surface b of the spreader bar at right angles thereto as shown in Figs. 4 and 5. It will be clearly seen that a sharp edge or corner e is formed at either side of the recesses at the top and bottom surface t and b respectively of the spreader bar. The corners e are sharp and well-defined as shown in Figs. 4 and 5 and are for a purpose to be hereinafter more fully explained.

Secured to the upper edge of the spreader bar S by means of a clamping plate 23 is a leaf spring 22 which extends lengthwise of the spreader bar and its free end is bent or flared upwardly at 24. This spring is preferably of considerable strength so that when flexed to permit the insertion of the tail piece of the pelt between the spring and the

spreader bar the tail piece will be firmly clamped in position.

As shown in Fig. 2 a fur pelt 26 is mounted in position upon the spreader frame. In using the stretching apparatus the pelt is turned inside out and the nose 9 of the spring frame is inserted into the pelt and the latter drawn over the frame. By grasping the spring arms and expanding them, the pelt may be stretched to the desired extent. It will be seen that when the arms 10 and 11 are thus spread outwardly the lower ends of the arms will slide freely in the guide slot 16 and 17 along the lower straight edges thereof as viewed in Fig. 3. When it is desired to clamp the arms in adjusted relative positions under tension, it is merely necessary to force the spreader bar S downwardly in a vertical direction thereby causing the arm 10 to enter one of the recesses or notches 20 and causing the arm 11 to enter one of the recesses 21. The tension exerted between the spring arms will hold them firmly in position within the notches by frictional engagement with one of the edge faces f of the adjacent teeth 18 and 19. The tail piece 27 of the pelt may thereupon be inserted beneath the spring 22 by grasping the bent up end 24 of the spring and flexing it sufficiently to permit the insertion of the tail piece between the spring and the spreader bar. Thereupon the tail piece may be stretched to the desired extent and when the spring 22 is released it will firmly clamp the tail piece in position.

In accordance with my present invention the spreader bar S is then forced downwardly to a slightly further extent to set up a tension between the pelt and the bar, and is then given a slight twist out of a horizontal plane as shown in Figs. 1 and 4 and into an angular position relative to the side arms of the frame as shown in Figs. 2 and 5. The spreader bar is twisted until two of the sharp edges or corners e of one of the recesses 20 and 21 grip or bite against the opposite edges of the side arms 10 and 11 respectively. Friction is thereby established at these points of engagement between the spreader bar and the side arms of the frame which locks the spreader bar in place and thereby holds the tail of the pelt under tension. With the spreader bar in this position (Figs. 2 and 5), the upward pull exerted by the tail of the pelt at the center of the bars will be firmly resisted, thereby holding the pelt stretched longitudinally of the frame. To unlock the bar and release the tension on the pelt it is simply necessary to exert a slight upward pull on the depressed end of the bar which quickly returns the parts to normal position shown in Figs. 1 and 4.

From the foregoing it will be seen that the spring frame may be easily expanded or contracted under tension against the fur pelt and locked in such expanded or contracted posi-

tion by means of the spreader bar S it being merely necessary to shift the latter in a direction transverse to the movement of the spring arms so as to cause the arms to enter the recesses 20 and 21. In addition it will be seen that the spreader bar S is easily and conveniently locked to the side arms of the frame and that the pelt is not only stretched in a transverse direction but is also held under tension in a longitudinal direction by the spreader bar, the locking mechanism for holding the bar in adjusted position being of very simple construction, it being only necessary to provide the teeth therein with parallel surfaces terminating preferably in sharp edges or corners at the upper and lower surfaces of the bar.

It will be noted, referring to Figure 5, that when the spreader bar is angularly disposed with relation to the spring arms, the gripping points e are diagonally disposed or in staggered relation with respect to the arms and the curvature or bowed condition of the arms provides an efficient binding action against opposite sides of each arm at longitudinally spaced points.

What I claim is:

1. A pelt stretcher comprising a frame having spring arms and a spreader bar for connecting said arms, said bar being provided with notches to receive said arms, said notches having portions frictionally locking said arms when said bar is in one angular position with respect to the arms, and said arms being freely movable into and out of said notches when said bar is in another angular position.

2. A pelt stretcher comprising a frame having spring arms and a spreader bar for connecting said arms, and having means for engaging and holding a portion of the pelt under tension, said bar being provided with notches to receive said arms, said notches having portions frictionally locking said arms when said bar is in one angular position with respect to the arms, and said arms being freely movable into and out of said notches when said bar is in another angular position.

3. A pelt stretcher comprising a frame having spring arms and a spreader bar for connecting said arms, said bar being provided adjacent each end with a series of notches for selectively receiving the adjacent arm, said notches having portions frictionally locking said arms when said bar is in one angular position with respect to the arms, and said arms being freely movable into and out of said notches when said bar is in another angular position.

4. A pelt stretcher comprising a spring frame having expandable and contractable spring arms and a spreader bar having a longitudinal guide slot for slidably receiving each arm, said slot having formed at one lon-

- 5 longitudinal edge a plurality of teeth having recesses therebetween of slightly greater width than the thickness of the arms to receive and lock said arms in adjusted position, 5 said teeth being provided with substantially parallel faces forming corners therebetween to frictionally engage and lock the side arms when the spreader bar is angularly disposed with relation to said arms.
- 10 5. A pelt stretcher comprising a spring frame having relatively expandible and contractable spring arms, a spreader bar, a flat spring carried by said bar for clamping the tail piece of the pelt thereto, said bar having 15 a guide slot for slidably receiving each arm of the frame, said slot having formed at one longitudinal edge a plurality of teeth having recesses therebetween of slightly greater width than the thickness of the arms, said 20 teeth being provided with substantially parallel faces providing diagonally disposed corners for frictionally gripping the arms

when the spreader bar is angularly disposed with relation to said arms.

6. A pelt stretcher comprising a frame 25 having spring arms, a spreader bar connecting said arms together, said bar having notches adapted to slidingly receive said arms and adapted when the bar is angularly disposed with relation to the spring arms to 30 bind against the opposite sides of the arms at longitudinally spaced points.

7. A pelt stretcher comprising a frame having spring arms, a spreader bar connecting said arms together, said bar having a series of notches for adjustably and slidingly receiving each arm, each notch having opposite walls adapted when the bar is angularly disposed to frictionally bind against the opposite sides of the arms at points spaced 35 40 longitudinally of the arms.

In testimony whereof I affix my signature.

JOHN J. SMITH.
